UNITED STATES PATENT OFFICE.

SIMON PINOVER, OF NEW YORK, N. Y., ASSIGNOR TO KAUFMANN BROTHERS,
OF SAME PLACE.

IMPROVEMENT IN WATCH-CHAIN LOCKS.

Specification forming part of Letters Patent No. **104,640**, dated June 21, 1870.

To all whom it may concern:

Be it known that I, SIMON PINOVER, of the city, county, and State of New York, have invented a new and Improved Chain-Lock; and I do hereby declare that the following is a full, clear, and exact description thereof, which will enable others skilled in the art to make and use the same, reference being had to the accompanying drawings, forming part of this specification.

My invention relates to a new article of manufacture for attaching watch chains or guards to vests, to be supplied to and sold by jewelers; and it consists in the device hereinafter described.

Figure 1 is partly a vertical section and partly a side view of my improved lock, and Fig. 2 is an enlarged detail section.

Similar letters of reference indicate corresponding parts.

A is the case, which is arranged similarly to ordinary padlock-cases, and it has a staple or eye, B, at the bottom, for the connection of the chain C.

The hasp D is provided with a hook, E, on the end, and projects into a sliding tubular catch, F, to be locked, passing through the lock-case G, and a fixed tube, H, which the catch-tube slides in, and which holds the spring I, that drives the catch-tube outward and holds it in the position to lock the hasp.

The tube H extends through the lock-case from side to side, and is closed at one side by the cap K, soldered onto the case, and to the end of it, to secure it and the spring at the other end, it receives the sliding catch-tube F, which is slotted at L for the reception of the stud-pin M, fixed in the tube H below, to prevent the spring from pushing it out. The said catch-tube is also provided with a thumb-bit, N, to be used in pushing it in to release the hasp. The bevel-hook pushes the catch back when the hasp is forced home.

This arrangement is very simple, and may be cheaply constructed. After the case has

been made and the round holes bored or otherwise formed for the tube H, the sliding catch-tube is first put into tube H and secured by the stud-pin M. Then the spring is put in, and the tube is put in place by sliding it in through one of the holes in the case. Then the cap K is put on, securing the tube in its place and confining the spring.

The compact arrangement of the tubes and other operative devices in the upper portion of the case A leaves a vacant space in the lower part of the same, which may be utilized as a receptacle for a photograph or other picture, and thus answer the purpose of a locket.

I am well aware that the devices employed in my invention are not new, *per se*, and also that a sliding three-pronged spring-plate and a hook are shown in the patent of S. Bogert, No. 41,191, January 1, 1864. I therefore desire to disclaim said patent, as my invention pertains to a new article of manufacture, superior in point of simplicity, mode of construction, facility of operation, and adaptation to its special use, and which is at the same time highly ornamental.

Having thus described my invention, I claim as new and desire to secure by Letters Patent—

The new and improved article of manufacture herein described, consisting of the padlock-case A, provided with the chain-eye B, stationary outer tube, H, having cap K, and containing the spiral spring I, the tube F, provided with the cap N, and slotted on one side to receive the hook E of the hasp D and on the other to receive the stud-pin M, all constructed and arranged as and for the purpose described.

The above specification of my invention signed by me this 26th day of May, 1870.

SIMON PINOVER.
